UNITED STATES PATENT OFFICE.

JOSEPH A. FIRSCHING, OF UTICA, NEW YORK.

KNITTING MACHINE.

Application filed November 15, 1921. Serial No. 515,204.

To all whom it may concern:

Be it known that I, JOSEPH A. FIRSCHING, of Utica, in the county of Oneida, in the State of New York, have invented new and useful Improvements in Knitting Machines, of which the following, taken in connection with the accompanying drawings, is a full, clear, and exact description.

This invention relates to certain improvements in knitting machines, and pertains more particularly to means for applying oil to the needles of such a machine.

It has been a quite general custom to apply oil at frequent intervals to the so-called "presser", used in spring knitting machines for closing the needle burr, in order to eliminate friction as far as possible, and thereby avoid heating of the needles and presser, which often results in breakage of the needles, uneven and inferior stitches, etc.

The application of oil to and by the presser results in considerable waste of oil, and very often in the distribution of oil upon the knitted cloth and thread, and requires frequent attention. The object of my invention is the production of an efficient and economic means requiring very infrequent attention for applying oil to the needles without danger of the oil being distributed upon the cloth or thread. The efficiency of the hereinabove described is such that the speed of the machine can be materially increased without heating the needles or the presser.

Other objects and advantages relate to the details of construction of the mechanism, all as will more fully appear from the following description, taken in connection with the accompanying drawings, in which:

Figure 1 is a top plan view of the oiling device.

Figure 2 is a sectional view of the same.

Figure 3 is a side elevation of the same.

The invention as here illustrated, comprises the combination with the needles 1 of the knitting machine, of a rotary absorbent disk 2 of felt or similar suitable material arranged for contact with the needles 1 adapted to be rotated by such a contact when the needles are rotating in the usual manner. This disk 2 applies the oil to the moving needles.

For the purpose of supplying oil to the disk in suitable quantities for application to the needles, various mechanisms and structures may be utilized, that shown be-

ing illustrative of a perhaps preferred construction, so far as my present experience teaches. The disk 2 , as shown, is secured between the members 3 and 4 , the member 3 being provided with a laterally extending bearing 5 upon which the disk 2 is mounted, and with a reduced threaded end portion 6 , upon which the internally threaded member 4 is mounted, so that upon relative movement of the members 3 and 4 in one direction, the disk 2 is gripped tightly between said members so that the feed of oil thereto, as hereinafter described, can be regulated, if desired, by compression of the disk. The member 4 is provided with an annular groove or recess 7 constituting an oil well for receiving an retaining the oil and feeding the oil thru a series of openings or perforations 8 in the bottom wall of said recess to the absorbent disk or pad 2 . This structure, consisting of the absorbent disk 2 and the supporting and retaining member 4 , the latter of which is adapted to receive, retain and feed the oil through the disk 2 , is mounted in a rotatable manner upon a stud or journal 9 , provided with a head 10 at its upper end formed with an oil receiving space or recess 11 leading to a lateral conduit 12 adapted to supply oil from said recess to the interior of the bearing 5 . This post may be supported in any suitable manner from the frame of the machine, and for this purpose is shown as carried by an arm 13 having an opening through which the stud 9 extends and to which it may be secured in various relative positions by means of adjusting screw 14 .

The oiling structure proper, consisting of the disk 2 and clamping members 3 and 4 , is loosely and rotatably mounted upon the stud 9 so that frictional contact with the rotating needles 1 will cause similar rotation of the disk 2 to adequately supply oil to the needles without material friction or strain upon any of the parts.

It is found in actual practice that it is only necessary to apply oil to the annular groove or wall 7 about once a day at infrequent intervals, and that this method of supplying oil to the needles saves a considerable percentage of the amount of oil ordinarily used, and further, the cloth does

not get saturated with oil, nor is there any material heating of the needles or the presser.

Although I have shown and described a specific construction and arrangement of parts, as illustrative of a perhaps preferred embodiment of my invention, I do not desire to limit myself to the details of form, construction or arrangement of the same, as various changes may be made therein without departing from the invention, as set forth in the appended claims.

I claim:

1. An oiling device for rotary knitting machines comprising a felt disk having a portion of its periphery in the path of movement of the needles, and means for rotatably supporting said disk to permit its free rotation by contact with the needles.
2. An oiling device for rotary knitting machines comprising an oil containing retaining disk having a portion of its periphery in the path of movement of the needles

of the machine, means for rotatably supporting said disk to permit its free rotation with the needles, a receptacle above said disk, and means of communication between the receptacle and the disk for supplying oil to the latter from the former.

3. An oiling device for rotary knitting machines comprising a felt disk having a portion of its periphery in the path of movement of the needles, means for rotatably supporting said disk to permit its free rotation by contact with the needles, a receptacle above said disk, and means of communication between the receptacle and the disk for supplying oil to the latter from the former.

In witness whereof I have hereunto set my hand this 3d day of November, 1921.

JOSEPH A. FIRSCHING.
